BOILER

Horace H. Peek, Sr., Chattanooga, Tenn.

Application July 24, 1937, Serial No. 155,437

3 Claims. (Cl. 122—74)

This invention relates to improvements in boilers and has special reference to improvements in the type of boiler shown in the Birchfield Patent No. 1,393,741 of which patent I am now the owner.

5 The boiler disclosed in said patent has a fire-box shell arranged within an outer shell and surrounded by water spaces, also the side sheets and the main crown sheet of the fire-box are preferably made from a single sheet bent to provide 10 dependent side sheets and a downwardly curved crown sheet which is joined, at its side edges, to the side sheets by reversely curved portions.

This patented boiler was developed and has been largely if not exclusively used for what is 15 termed "low-pressure heating".

However, the modern development has been in the direction of higher pressures, and the present invention relates especially to improvements in said type of boiler by which it can be 20 safely used for producing the high pressures now being demanded both for heating and power purposes.

The peculiar form of boiler construction of said 25 patented boiler has many important features which it is desired to retain in high-pressure boilers but when this form of boiler construction is subjected to the high pressures desired, weaknesses are developed which it is the special object of this invention to overcome.

30 It is one object of this present invention to provide stiffening, bracing or strengthening members for this type of boiler construction which shall permit this form of construction to be safely used for the high pressures desired.

35 It is a further object of the invention to provide an improved construction, in this regard, over that shown in U. S. Patent No. 2,079,503 of which I am now the owner, in that I arrange the stiffening, bracing or strengthening members within 40 the interior of the boiler where they are protected from direct contact with the fire-box gases of combustion.

It is obvious that the high internal forces to 45 which the production of high pressures will subject the boiler would not only tend to spread the side walls of the outer shell but would also tend to depress the downwardly curved main crown sheet and draw the reversely curved portions inwardly from the side sheets of the outer shell, thus producing destructive or distorting actions which it is the object of this present invention to prevent or overcome.

Due to the location of the braces or stiffening 50 or tension or distortion members at or near to

the tops of the reversely curved portions of the fire-box shell they are entirely surrounded by the water in the boiler, and thus protected from destructive changes in stresses and strains and due to their location the stresses which the braces 5 oppose are produced mainly by tension or distortion.

These stiffening members may be in the form of single units either welded or riveted to and upon the reversely curved portions of the fire-box 10 shell or they may also be joined or attached to the outer shell, thus connecting the inner and outer shells in a manner to prevent distortion thereof, or the stiffening members at opposite sides of the crown-sheet may be tied together by 15 tension plates, or in other forms oppositely disposed stiffening members may be connected together, and to the outer shell.

In other forms instead of single stiffening units they may be made in multiple form, that is, a 20 number of stiffening members may be connected together, longitudinally of the boiler, and preferably also connected to the outer shell.

But whatever form of the invention is found best under any certain set of circumstances the 25 fundamental idea is preserved of applying varied forms or shapes of stiffening, bracing or strengthening members to the reversely curved side edge portions of the fire-box shell and which members are arranged within the interior of the boiler and 30 thus protected from the gases of combustion.

Other features of advantage and benefit will 35 become apparent from the following description taken in conjunction with the appended claims and the accompanying drawings forming part of this specification. It should be understood however that such drawings and description are typical merely of my invention and that my invention is not to be limited in anywise thereby.

In said drawings:—

Fig. 1 is a vertical, central, longitudinal section on the line 1—1 of Fig. 2 of a boiler of the type mentioned and showing a simple form of the invention;

Fig. 2 is a fragmentary, vertical, transverse section taken on the line 2—2 of Fig. 1 and showing the form of the invention portrayed in Fig. 1;

Fig. 2a is similar to Fig. 2, but shows a slightly modified form of the invention;

Fig. 3 is a section similar to Fig. 2, and showing 50 still another form of the invention;

Fig. 4 is a fragmentary, horizontal section on the line 4—4 of Figs. 1 and 2;

Fig. 5 is a section similar to Fig. 4 but taken on the line 5—5 of Fig. 2a;

Fig. 6 is a fragmentary, horizontal section similar to Fig. 5 but showing a riveted instead of a welded construction;

Fig. 7 is a fragmentary, vertical section similar to Fig. 2a, but taken on the line 7—7 of Fig. 6;

Fig. 8 is a fragmentary, horizontal section on the line 8—8 of Fig. 3;

Fig. 9 is a fragmentary, horizontal section similar to Fig. 4 but showing another modification of 10 the invention;

Fig. 10 is a fragmentary, vertical, transverse section on the line 10—10 of Fig. 9;

Fig. 11 is a fragmentary, vertical section similar to Fig. 4 but showing another slightly modified 15 form of the invention; and

Fig. 12 is a fragmentary, vertical section on the line 12—12 of Fig. 11.

The boiler shown in the drawings has an outer shell 15 of inverted U-shape and within this shell 20 is arranged an M-shaped fire box 16 separated from the outer shell by side water legs 17, a front water leg 18 and a rear water leg 19.

Preferably as shown, the fire-box 16 is made up mainly of a single sheet of sheet metal formed 25 to provide downwardly extending side sheet portions 20, a downwardly curved crown sheet portion 21 which is connected at its side edges with the side sheet portions by upwardly or reversely curved portions 22, of relatively small radius.

30 The lower edges of the outer boiler shell and the fire-box shell are co-incident and the lower ends of the water legs which are provided between these two shells are closed by a bottom ring 23. This ring 23 fits between the inner and outer 35 boiler shells and is preferably welded at its inner and outer edges to the inner and outer shells as shown at 24.

40 The downwardly curved crown sheet portion rounds out the body of the boiler which is mainly formed by the outer sheet 15 and provides capacity for more fire flues than if it were curved upwardly.

As usual the outer and inner sheets of the boiler are connected by suitable stay bolts 25.

45 In the form of boiler shown, the fire-box has a main combustion chamber 26 below the crown sheet 21 and an auxiliary combustion chamber at the rear end of the boiler which rises above the main crown sheet as shown at 27.

50 As usual the fire-box is closed at its front end by a vertical sheet 28 and at its rear end by a vertical sheet 29 which preferably is formed at its upper end to close the top of the auxiliary combustion space. The forward end of the auxiliary combustion space is closed by a vertical flue sheet 30. The outer shell is completed by a vertical sheet 31 at the front end of the boiler and a vertical sheet 32 at the rear end of the boiler.

60 Horizontal fire flues 33 lead forward from the auxiliary flue sheet 30 to the front boiler sheet 31 and a second set of horizontal fire flues 34 above the flues 33 lead rearwardly from the front boiler sheet 31 to the rear boiler sheet 32.

65 It should be understood that, to complete the boiler for use, a smoke box is added at the front of the boiler to guide the flue gases from the lower set of flues to the upper set of flues and that a suitable smoke pipe is provided to connect the rear end of the boiler to a suitable stack for carrying away the flue gases.

It is a special object of this present invention to so strengthen and stiffen the upper part of the fire-box including the downwardly curved 75 crown sheet 21 and the reversely curved portions

22 at the lateral edges of the crown sheet that this construction of boiler can be safely used for the high pressures desired.

For this purpose I provide stiffening and strengthening members which embrace the reversely curved portions 22 and are rigidly secured thereto and which lie wholly within the interior of the boiler within the water space thereof.

The most simple form of such stiffening members is shown in Figs. 1, 2 and 4 at 35, and consists of a vertical central plate 36 arranged to span one of the portions 22. This plate 36, as shown, is arranged transversely of the boiler and its lower edge is cut out, as shown at 37, to fit on the reversely curved portion 22.

Preferably the plate 36 is made more rigid by applying metal angle pieces 38 thereto, as shown, two angle pieces on each side and the adjacent legs of these angle members are rigidly connected together. The stiffening unit thus formed may 20 be secured to and on the reversely curved portion 22 by welding as shown by the heavy line 39 or the lower edges of the plates 36 may be bent to form a flange 40 for contact with the reversely curved portion 22 and the unit connected to the 25 reversely curved portion by rivets as indicated in Fig. 6.

It is usual to provide a plurality of these stiffening units 35 at each side of the boiler, four such units being shown in Fig. 1, spaced along the reversely curved portion 22.

While this simple form of stiffening unit is effective for pressures higher than those ordinarily used in low pressure heating, I have found that it is best, for some pressures, to connect the 35 units 35 to the outer shell preferably by extending the central plate 36 to meet the outer shell as shown in Figs. 2a and 5 at 41 and securing it to the outer shell preferably by welding as shown at 42, although in some instances its outer edge 40 portion may be bent off at a right angle as shown at 43 Figs. 6 and 7 and the unit connected to the outer shell by rivets as shown.

Under still other conditions, such as extremely high pressures, I have found that it is best to 45 cross connect the units arranged at the opposite sides of the boiler. Preferably I accomplish this by providing transversely extending plates 44, Fig. 3, which are preferably though not necessarily continuations of the central plates 36. 50 These transverse plates, which may be termed tension plates, are provided with suitable openings 45 to permit the installation of the lower fire flues 33.

Obviously, when the tension plates 44 are used, 55 they may be extended through the stiffening units to the outer shell and their transverse ends connected to the outer shell preferably by welding as indicated at 46, or their outer ends may be bent at right angles to form a flange 47 adapted 60 to be secured to the outer shell by rivets as indicated in Fig. 8.

In Fig. 9, I have shown another form 48 of the invention.

This form consists of a plurality of the plates 36 connected together at their inner edges by a longitudinal plate 49 and at their outer edges by a similar longitudinal plate 50. This multiple unit may be further stiffened by providing flanges 51 on the center plate 52 and securing this center 70 plate to the plates 49 and 50 by rivets as shown in Figs. 9 and 10. As in the other forms of the invention this multiple unit may be connected to the outer shell of the boiler. When this is desired, I preferably extend the ends of the outer 75

longitudinal plate 50 as shown at 53 and form them into contact with the outer shell and obviously they can be rigidly connected to the outer shell by rivets as shown or by welding.

5 In Figs. 11 and 12 I have shown a very simple form of stiffener.

This form as shown at 54 is made up of a piece of I-shaped structural steel which is formed to fit upon the reversely curved portion 22 and preferably the member is of such a size that its outer end 55 fits snugly between the outer and inner shells of the boiler as shown in Fig. 11.

The form of this unit, being provided with inner flanges 56 and outer flanges 57 lends itself 15 for being readily secured upon the reversely curved portion 22 and to the outer shell by rivets as shown.

In the application of my improvements to various boilers it is preferable to secure the stiffening members by welding, when applied to a welded boiler and by rivets when applied to a riveted boiler.

I claim:—

1. In a boiler having a fire-box shell within an outer shell and separated therefrom by water spaces, the fire-box shell having depending side

sheets and a downwardly curved crown sheet joined at its lateral edges to the side sheets by reversely curved portions, vertical, transversely extending, stiffening plates formed on their lower edges to fit upon said reversely curved portions, 5 means permanently securing the lower edges of said plates to and upon said reversely curved portions, and means permanently connecting the outer ends of said plates to the proximate side wall of the outer shell as and for the purpose 10 specified.

2. The invention as defined in claim 1, and a transverse tension plate connecting oppositely arranged stiffening plates.

3. In a boiler having a fire-box shell within 15 an outer shell and separated therefrom by water spaces, the fire-box shell having depending side sheets and a downwardly curved crown sheet joined at its lateral edges to the side sheets by reversely curved portions, tension members ex- 20 tending across the boiler, within the water space thereof and permanently secured to the outer shell of the boiler and to said reversely curved connecting portions of the fire-box shell.

25

HORACE H. PEEK, SR.
